UNITED STATES PATENT OFFICE

EDGAR R. TILLBROOK, OF ERIE, PENNSYLVANIA

DESIGN FOR AN ALARM CLOCK STAND

Application filed December 20, 1930. Serial No. 38,046. Term of patent 3½ years.

To all whom it may concern:

Be it known that I, EDGAR R. TILLBROOK, a citizen of the United States, residing at Erie, in the county of Erie and State of Pennsylvania, have invented a new, original, and ornamental Design for Alarm Clock Stands, of which the following is a specification.

In the accompanying drawings, forming a part of this specification:

alarm clock stand, showing my new design.

I claim:

The ornamental design for an alarm clock stand, as shown.

In testimony whereof I affix my signature.

EDGAR R. TILLBROOK.
